UNITED STATES PATENT OFFICE

PERRY S. MCCALLEN, OF KNOXVILLE, TENNESSEE, ASSIGNOR TO HUGH W. SANFORD, OF KNOXVILLE, TENNESSEE

MINE CAR

Application filed January 29, 1930, Serial No. 424,206. Renewed August 11, 1931.

My improvement relates to mine or similar cars having a middle, longitudinal discharge opening and a shiftable bottom normally closing said opening and said bottom being adapted to be shifted for discharge when the car is at the place for discharge, thereby allowing the load to discharge downward by gravity from the interior of the car body.

10 The object of my improvement is to give such a car greater lading capacity without increasing the height and width of the car.

Accordingly, my present improvement, as will be fully described further on, includes 15 side structures for supporting lading at each side of said longitudinal discharge opening, said side structure having a bottom adapted to normally hold lading at the sides of the discharge opening, and said side structures 20 being arranged for automatic shifting to incline their bottoms toward the discharge opening sufficiently to cause the lading supported thereon to slide into the discharge opening.

25 For an example of such a car of this general type, I refer to United States Patent, No. 1,268,390, granted to Hugh W. Sanford, June 4, 1918.

In that car there is a main frame comprising 30 side sills and end sills or end structures connecting the ends of the side sills; and doors are placed to fill the space between said side sills and said end sills, the doors being hinged by their forward ends on axes which 35 are horizontal and transverse to the side sills. The doors are inter-related by being formed to inter-engage each other when in the closed position, and a latch mechanism engages the rear end of the rear door when the doors are 40 in the raised position. When that latch mechanism is released, the rear door turns downward on its hinged axis and releases the next forward door. That door then turns downward by gravity and releases the next forward door, if there 45 is a third door. The latch mechanism is arranged for automatic releasing by engagement with a cam stationary beside the track at the tipple or other place at which the load 50 is to be discharged. On the track, between

the track rails is a cam positioned to successively engage the open doors and raise them into the closed position, or a little higher than the closed position, during the forward movement of the car. The latch mechanism 55 makes its engagement with the rear door automatically during the upward movement of that door for its closing. Then the doors are firmly held ready to receive a new load. In United States Patent, No. 1,512,059, granted 60 to Hugh W. Sanford, October 21, 1924, a single door is substituted for the plurality of doors shown in the above-mentioned Patent No. 1,268,390.

In both the above-mentioned patents, body 65 side walls rise from the side sills. These walls are stationary and upright far enough to allow them to lean outward above the car wheels. By thus leaning outward the car body is given greater lading capacity. But, 70 because they are stationary, these walls must not lean farther than the angle of repose, the slant which allows the coal or other lading to slide downward when the lading supported by the bottom doors descends after those 75 doors have been opened.

As above indicated, the object of this invention is to provide lateral extensions of the car body without limiting them to a slant which would allow the lading to slide into 80 the space between the side sills or the space controlled by the bottom door or doors.

Accordingly my improvement includes—
(1) a bottom door or doors constituting a main bottom and (2) body side sections or 85 structures having auxiliary bottoms or floors too low, when in the normal or lading position, to discharge lading by sliding into the main bottom opening.

These body side structures are made shift- 90 able to permit bringing them into position to discharge their lading into the middle, longitudinal discharge opening by sliding. In the particular structure illustrated by the accompanying drawings, these side structures are 95 hinged on lines parallel to the side lines of the discharge opening; and provision is made for automatically turning these side structures on their hinges when the car arrives at or is passing the tipple or other discharge 100

place. Provision is also made for automatically opening the bottom by releasing the door latch mechanism, that being done before the side structures are turned.

As will be seen further on, the floors of the side structures are approximately horizontal and at the level of the side sills or approximately at the level of the main bottom formed by a door or doors.

In the accompanying drawings,

Fig. 1 is a sectional elevation along a mine car tipple, showing the track structures and a cam for releasing the door latch mechanism and showing a cam for turning or tilting one of the car body side structures and showing a cam for raising the bottom door or doors into the closed position and showing a car approaching the cams, it being understood that the travel of the cars is from the left toward the right;

Fig. 2 is a plan of the track structure shown by Fig. 1;

Fig. 3 is a side elevation of a car embodying my improvement and having its three bottom doors closed and its body side structures in the lower or closed positions;

Fig. 3a is a transverse, upright section on the line, 3a—3a, of Fig. 3, looking toward the left;

Fig. 4 is an elevation of the rear or left hand end of the car shown in Fig. 3;

Fig. 5 is an elevation of the forward or right hand end of the car of Fig. 3;

Fig. 6 is a plan of the same car, the main bottom being closed and the body side extensions or structures being in the closed or normal position;

Fig. 7 is an upright longitudinal section on the line, 7—7, of Fig. 6, looking in the direction of the arrows;

Fig. 8 is a horizontal sectional on the line, 8—8, of Fig. 7;

Fig. 9 is an upright transverse section on the line, 9—9, of Fig. 3, looking toward the left;

Fig. 10 is a transverse upright section on the line, 10—10, of Figs. 3, 6, 7 and 11, the side structures being in the raised or discharge positions;

Fig. 11 is an elevation like Fig. 3, the right hand side structure being in the raised or discharge position;

Fig. 12 is an end elevation of one of the side extensions;

Fig. 13 is a section on the line, 13—13, of Fig. 14;

Fig. 14 is a transverse section like Fig. 9, a stationary wall being placed above the hinged side structure.

Referring to said drawings, A, A are track rails resting on ties, A1, and piers, A2. A3 is a door-raising cam between the rails, A, A. B, B are ordinary car wheels applied to the ends of axles, C, C, extending through bearings, Ci, seated on the side sills, D, D. The

ends of those side sills are joined by transverse end structures, D1. The side sills and the end structures together form a main frame.

The side sills are shown of channel form; but it is to be understood that they may be of any suitable form.

In the form shown in the drawings, the end structures, D1, comprise, as a main element, a plate metal member having an upright or back web, D2, a lower outward-directed flange, D3, and an upper outward-directed flange, D4. Other members of said structure are similar to the structure of Figs. 1, 2 and 11, inclusive, of United States Patent, No. 1,486,547, granted to Hugh W. Sanford, March 11, 1924. Attachment between the side sills and the end structure is made by means of angle members, D5, having one arm riveted to the inner face of the web, D2, and having its other arm resting between the flanges of the adjacent side sill and against the upright web of said sill and riveted to said web, as is described in said patent, No. 1,486,547.

The space between the side sills and the end structures is to be regarded as the discharge opening; and that opening is normally closed by the shiftable bottom. In the form shown by these drawings, three bottom doors, E, E1 and E2, are used to normally close said opening and those doors constitute the main or middle bottom of the car.

The rear door, E, has its forward end hinged to the rear axle, C, by means of hinge straps, C2, surrounding the axle and suitably secured to the underface of the door. The second or middle door, E1, has its forward end hinged to the forward axle, C, by means of hinge straps, C2, surrounding said axle and suitably joined to the lower face of said door. The forward door, E2, has its forward edge hinged to a transverse horizontal hinge rod, C3, by means of hinge straps, C2, surrounding the hinge rod and suitably secured to the lower face of said door. The ends of the hinge rod rest in the side sills, D. At their side edges, the doors have upright flanges, E3, overlapping the inner faces of the adjacent side sills, D.

At each end of the car, two brackets, F, rise from the upper flange, D4, of the end structure, at opposite sides of and equally distant from the upright middle longitudinal plane of the car. Each bracket has a lower horizontal flange, F1, resting on and riveted to the upper end structure flange, D4. And each bracket has at its upper end a horizontal flange, F2, on which rests a horizontal frame end rail, G, extending outward to the outer limits of the car body and there meeting the frame side rails, G1. For convenience in construction, each side rail and the adjacent half of each end rail are made unitary, these rails being shown of channel 13

form and the flanges of the channels being cut away where the rails are bent at the corners of the frame thus formed.

At each end of the car an end wall plate, 5 H, is applied to the inner face of the adjacent end rail, G, from one side rail, G1, to the other and has oblique edges extending downward to the top of each side sill, D, and across said sill and thence downward and obliquely 10 toward the middle of the car and between the side flanges, E3, of the adjacent doors. A part of the plate, H, which overlaps the end rail, G, is secured to the end rail by means of bolts or rivets. Midway between the ends of 15 the end rail, G, the joint in said rail is overlapped by a reinforcing plate, G2, and rivets or bolts extend through said plate and the rail, G, and the end wall plate, H. The end rails, G, and the side rails, G1, constitute a 20 second or upper frame.

From each side frame rail, G1, downward to the adjacent side sill, D, the inner face of the end wall plate, H, is overlapped by a reinforcing bar, H1, and riveted to said bar. 25 A gusset plate, H2, overlaps the outer face of the plate, H, and is secured to said plate by a part of the rivets which extend through the bar, H1, and the wall plate, H. The gusset plate extends downward to the adjacent 30 angle member, D5, and has a foot, H3, leaning against the adjacent arm of the angle member and riveted thereto.

By the means last above described, the end wall plates and the second frame formed by 35 the end frame rails, G, and the side frame rails, G1, are rigidly supported.

When the doors are free and the load has been discharged, the forward movement of the car brings the doors successively against 40 the door-raising cam, A3, whereby the doors are raised into the closed position the rear door being then latched, as next described.

As a part of the latch mechanism for the rear door, a standard, I, rises from the upper 45 face of the upper flange, D4, of the adjacent end structure, D1, the standard having a horizontal foot, I2, resting on the upper face of said flange and riveted or bolted thereto. The upper end of said standard extends to 50 toward the adjacent end wall plate, H, and then downward. An approximately horizontal latch arm, I2, rests in the space formed by thus folding the standard, I. A pintle or bolt, I3, extends horizontally through the

55 two parts of the standard and through said arm and the adjacent part of the end wall plate, H. Thus the arm, I2, may rock on said pintle. Said arm extends through a slot, F3, in the adjacent bracket, F, the slot

60 being long enough in the up and down direction to allow said arm to move up and down. A hook, I4, extends downward from the arm, I2, in position to engage a wrist, E4, on the rear edge of the rear door, E, when the arm, I2, is in its lower position and said door is

in the closed position. Thus that door is held in the closed position until the arm, I2, is raised by the cam, I5, placed beside the track in the path of said arm. The slot, F3, in the bracket, F, is preferably extended 70 downward only as far as the lower edge of the arm, I2, when the hook, I4, is in engagement with the wrist, E4. Thus, after passing the cam, I5, the arm will automatically move into its lower position and return the 75 hook into position to again engage the wrist, E4, when the rear door is again raised.

The lower end of the hook, I4, has a slanting edge, I6, against which the wrist, E4, bears during its upward movement while the rear door is being raised. (Fig. 3a). Thus 80 said wrist pushes the hook sidewise, until said wrist is above the point of the hook. Then the weight of the arm, I2, moves said arm downward, and that moves the hook toward and under the wrist, E4. The weight of the arm, I2, may be made sufficient to effect this movement; but the drawings show a contracting coiled spring, I7, having one end attached to the hook and having its other end attached to the bracket, F, which is the farther from the arm, I2. The force of this spring is added to the gravity action on the arm, I2, to move said arm and the hook, I4, into rest position.

The body side structures or extensions are 85 duplicates. Hence a description of one will serve for both. Each such structure has a floor, J, resting on the upper flange of the adjacent side sill, D, and extending thence outward horizontally approximately to the plane of the inner face of the adjacent second frame side rail, G1. From said floor approximately 90 over the inner face of the side rail, G1, extends upward over the inner face of the side rail, G1. An outward-directed flange, J2, formed on the upper edge of the wall, J1, normally rests on the upper edge of the frame side rail, G1, whereby one support for the side extension 95 of the car is formed. Hinges, J3, are attached to the inner face of the adjacent side sill, D, and the adjacent upper face of the extension floor, J, whereby the extension may turn or rock on the axial line of those hinges. The drawings show three such hinges applied 100 to the extension.

When this extension is in normal or working condition, the flange, J2, rests on the adjacent second frame side rail, G1. Then the 105 only motion on said hinges may be a turning upward, the flange, J2, rising from the rail, G1.

Further support is given the side extension by engagement with the oblique reinforcing bar, H1, already described as lying against the inner face of the end wall plates, H. For this a reinforcing bar, J4, is applied to the outer face of the triangular end wall, J5, which is joined to the end edges of the floor, J, and the wall, J1, and is in a plane overlap- 110 115 120 125 130

ping the inner face of the reinforcing bar, H1, so that when this extension section is in its normal position or position of rest, the reinforcing bar, J4, will rest on the reinforcing bar, H1. Thus the body extension section 5 has three supports:— (1) the hinges, J3; (2) the second frame side rails, G1; and (3) the reinforcing bar, H1.

The car wheels, B, are higher than the upper face of the side sills, D. Hence the wheels 10 extend through the plane of the body extension floor, J. That requires forming openings, J6, in the floor, J, to receive the wheels. A hood, J7, extends over each wheel and has 15 flanges, J8, resting on and secured to the floor, J, and an upright flange, J9, resting against and secured to the inner face of the wall, J1.

To the lower face of the floor, J, approximately midway between its ends, and near 20 the upright wall, J1, is a downward-directed bracket, J10, which supports a roller, J11, in position to ride upward on the cam, J12, which is stationary at the side of the track 25 at the tipple or other place for discharge, said cam being in the path of said roller and said cam being twisted or deflected to keep in engagement with said roller while the roller is being carried upward and sidewise during the turning of the side extension. 30

By means of this cam said extension is to be tilted sufficiently to incline the extension floor, J, to an angle which will allow the coal or other lading resting thereon to slide from 35 that floor and into the discharge space between the side sills, D.

It is to be understood that the cam, I5, is to be located so as to be engaged by the cam, I2, for the release of the bottom doors, E, E1 and 40 E2, before the rollers, J11, reach the cams, J12, in order that the bottom doors may be discharging before the side structures or sections are lifted. It is also to be noted that the body side extensions are preferably independent 45 of each other so that a cam, J12, is needed at each side of the rail track.

As soon as the rollers, J11, are allowed to move downward from the cam, J12, the side extensions can move downward by the action 50 of gravity, that movement being on the hinges, J3.

In Fig. 14, there is shown a modification, wherein the side frame rail, G1, is placed higher than in the form illustrated by the preceding figures of the drawings. A metal plate or sheet, G3, is supported on the rail, G1, and extends downward from said rail. The upper edge of said plate is extended outward horizontally to rest on the upper edge 55 of the rail. Said plate is secured to the rail by means of rivets or bolts. Along its lower edge the plate, G3, is turned inward to form a flange, G4. The extension wall, J1, extends upward only far enough to allow its flange, 60 J2, to normally overlap the flange, G4.

By this means, the height of the car body above the floor extension, J, may be increased relative to what has been shown in the preceding figures of the drawings. If the height of the wall, J1, is made sufficient to bring a 70 plane extending from the hinges, J3, to the upper edge of said wall, J1, into the angle of repose, the coal or other lading above the upper edge of the wall, J1, will slide into the discharge space between the side sills, D1, 75 D1, before the side extensions are to be turned on their hinges.

The fixed parts of the car may be regarded as the car body. Those parts are the side sills, D, and the end structures, D1, and the end wall plates, H, and the gusset plates, H2, and the upper end rails, G, and the upper side rails, G1, and other minor parts. 80

It is to be observed that the rails, G and G1, extend outward farther than do the side sills, D, and farther than the edges of the end wall plates, H, and the gusset plates, H2, and that each hinged side structure extends downward below the rails, G and G1, and outward from the side sills and the end wall plates, H, and the gusset plates, H2. Thus each side of the car body has a lateral and downward opening through which the adjacent side structure extends. Thus each side structure is positioned to meet the cam, J12, which, 90 as above described, is placed beside the rail track at the tipple or other discharge station. Thus it may be said that the side structures extend downward from the upper part and outward from the lower part of the car body into position to meet the cams, J12, during the forward movement of the car. Or it 95 may be said that the car body has at each side a lateral and downward opening into which a side structure extends in position to meet the cam, J12, during the travel of the car. Or it may be said that the side structure is so supported on the car body as to be exposed 100 for engagement with lifting means placed along the rail track. 110

It is to be noted that the cams, J12, function as a lifting means placed at or adjacent the rail track in position to engage and lift the side structures, the lifting means being normally passive, the functioning being initiated by the moving car. 115

In mine cars it is advantageous to have the track wheels accessible for lubrication and for removal and replacing. In my improved car, although the side structures, when they are at rest, reach outward over the wheels and surround the upper parts of the wheels, the wheels are completely exposed and readily accessible when the side structures are turned upward. Thus, when the car is empty, access 120 may be had to the wheels after turning the side structures upward. 125

Any desired coupling means may be applied to the end structures, D1. This may be 130

a coupling pin, P, to engage a coupling link.

It is to be observed that the form of means for controlling the discharge opening between the side sills may be varied. For example, the single bottom door of United States Patent, No. 1,512,059, granted to Hugh W. Sanford, October 21, 1924, already herein mentioned, may be substituted for the three doors shown by the drawings in this application. The means for controlling said discharge opening may be in still other forms.

I claim as my invention,

1. In a mine or similar car, the combination of a wheel-supported body having a middle longitudinal discharge opening and said body having at each side a lateral opening, a movable bottom controlling said discharge opening, and a side structure at each side of said discharge opening and normally extending laterally into said lateral body opening into position to meet lifting means at the rail track and said side structures being normally positioned to receive and support a part of the lading or material constituting the load of the car and to retain a part of said lading after said movable bottom has been moved for discharge of lading through said discharge opening and said side structures being tilttable to discharge their lading through said discharge opening.

2. In a mine or similar car, the combination of a wheel-supported body having a middle longitudinal discharge opening and said body having at each side a lateral opening, a hinged bottom controlling said discharge opening, and a side structure located at each side of said discharge opening and normally extending laterally into said lateral body opening into position to meet lifting means at the rail track and said side structures being normally positioned to receive and support a part of the lading or material constituting the load of the car and to retain a part of said lading after said hinged bottom has been turned for discharge of lading through said discharge opening and said side structures being tilttable to discharge their lading through said discharge opening.

3. In a mine or similar car, the combination of a wheel-supported body having a middle longitudinal discharge opening and said body having at each side a lateral opening, a bottom hinged transversely in said discharge opening, and a side structure located at each side of said discharge opening and normally extending laterally into said lateral body opening into position to meet a cam beside the rail track and said side structures being normally positioned to receive and support a part of the lading or material constituting the load of the car and to retain a part of said lading after said hinged bottom has been turned for discharge of lading through said discharge opening and said

side structures being tilttable to discharge their lading through said discharge opening.

4. In a mine or similar car, the combination of a wheel-supported body having a middle longitudinal discharge opening and said body having at each side a lateral opening, a plurality of bottom doors hinged transversely in said discharge opening, and a side structure located at each side of said discharge opening and normally extending laterally into said lateral body opening in position to meet a cam beside the rail track and said side structures being normally positioned to receive and support a part of the lading or material constituting the load of the car and to retain a part of said lading after said doors have been opened for discharge of lading through said discharge opening and said side structures being tilttable to discharge their lading through said discharge opening.

5. In a mine or similar car, the combination of a wheel-supported body having a middle longitudinal discharge opening and said body having at each side a lateral opening, a plurality of longitudinal bottom doors hinged transversely in said discharge opening, automatic means for holding one of said doors in the closed position, and a side structure located at each side of said discharge opening and normally extending laterally into said lateral body opening in position to meet a cam beside the rail track and said side structures being normally positioned to receive and support a part of the lading or material constituting the load of the car and to retain a part of said lading after said doors have been opened for discharge of lading through said discharge opening and said side structures being tilttable to discharge their lading through said discharge opening.

6. In a mine or similar car, the combination of a wheel-supported body having a middle longitudinal discharge opening and said body having at each side a lateral opening, a plurality of door structures hinged transversely in said discharge opening and adapted to be engaged by means along the track for turning said doors into the closed position, and a side structure located at each side of said discharge opening and normally extending laterally into said lateral body opening in position to meet a cam beside the rail track and said side structure being normally positioned to receive and support a part of the lading or material constituting the load of the car and to retain a part of said lading after said doors have been opened for discharge of lading through said discharge opening and said side structures being tilttable to discharge their lading through said discharge opening.

7. In a mine or similar car, the combination of a wheel-supported body having a middle longitudinal discharge opening and

- said body having at each side a lateral opening, bottom doors hinged transversely in said discharge opening, automatic means for releasably engaging and holding the doors 5 when they have been moved into the closed position, and a side structure located at each side of said discharge opening and normally extending laterally into said lateral body opening in position to meet a cam beside the 10 rail track and said side structures being normally positioned to receive and support a part of the lading or material constituting the load of the car and to retain a part of said lading after said doors have been opened 15 for discharge of lading through said discharge opening and said side structures being tiltable to discharge their lading through said discharge opening.
8. In a mine or similar car, the combination of a wheel-supported body having a middle longitudinal discharge opening and said body having at each side a lateral opening, a movable bottom controlling said discharge opening, a side structure located at 20 each side of said discharge opening and extending laterally into said lateral body opening in position to meet a cam beside the rail track and each side structure having a bottom extending outward from said discharge 25 opening and each structure having a wall extending upward from the outer part of said bottom, and means on said car body for supporting said bottom and said wall of said structures.
- 30 9. In a mine or similar car, the combination of a wheel-supported body having a middle longitudinal discharge opening and said body having at each side a lateral opening, a movable bottom controlling said discharge opening, a side structure located at each side of said discharge opening and extending laterally into said lateral body opening in position to meet lifting means at the rail track and each side structure having a bottom extending outward from said discharge opening and each structure having a wall extending upward from the outer part of said bottom and being formed to rest on the adjacent side rail, and means on said car 35 body for supporting said bottom and the ends of said structures.
- 40 10. In a mine or similar car, the combination of a wheel-supported body having a middle longitudinal discharge opening and said body having at each side a lateral opening, a movable bottom controlling said discharge opening, a side structure located at each side of and hinged along said discharge opening and extending laterally into said 45 lateral body opening in position to meet lifting means at the rail track and each side structure having a bottom extending outward from said discharge opening and each structure having a wall extending upward from the 50 outer part of said bottom, and means on said 55 60 65
- car body for supporting said bottom and said wall.
11. In a mine or similar car, the combination of a wheel-supported body having a middle longitudinal discharge opening and said body having at each side a lateral opening, a movable bottom controlling said discharge opening, a side structure located at each side of said discharge opening and extending laterally into said lateral body opening in position to meet a cam beside the rail track and each side structure having a bottom extending outward from said discharge opening and each structure having a wall extending upward from the outer part of said bottom, means on said car body for supporting said bottom and said wall, and body end walls formed to engage the ends of the side structures.
12. In a mine or similar car, the combination of a wheel-supported body having a middle longitudinal discharge opening, a movable bottom controlling said discharge opening, and a side structure located at each side of said discharge opening and having a bottom in a plane cutting the wheels of the car and said bottom having hoods extending over said wheels and said side structures being shiftable to discharge their lading through said discharge opening.
13. In a mine or similar car, the combination of a wheel-supported body having a middle longitudinal opening, a movable bottom controlling said discharge opening, and a side structure located at each side of said discharge opening and having a bottom in a plane cutting the wheels of the car and said bottom having hoods extending over said wheels and said side structures being tiltable to discharge their lading through said discharge opening.
14. In a mine or similar car, the combination of a wheel-supported body having a middle longitudinal opening, a movable bottom controlling said discharge opening, and a side structure located at each side of said discharge opening and having a bottom in a plane cutting the wheels of the car and said bottom having hoods extending over said wheels and said side structures being hinged for tilting to discharge their lading through said discharge opening.
15. In a mine or similar car, the combination of a wheel-supported body having a middle longitudinal opening, a movable bottom controlling said discharge opening, and a side structure located at each side of said discharge opening and having a hinged bottom in a plane cutting the wheels of the car and said bottom having hoods extending over said wheels and said side structures being positioned to adapt them to engage a cam, placed along the rail track, for turning said structures on their hinges for discharge of

their lading into the longitudinal discharge opening.

16. In a mine or similar car, the combination of a wheel-supported body comprising side sills and end sills connecting the side sills, of a movable bottom controlling the space between the side sills and the end sills, and a side structure located at and extending laterally from each side sill in position to meet a cam beside the rail track and each side structure being normally positioned to receive and support a part of the lading constituting the load of the car and to retain a part of said lading after said movable bottom has been moved for discharge of lading through the discharge space between the side sills and said side structures being tilttable to discharge their lading through said discharge space.

20. 17. In a mine or similar car, the combination of a wheel-supported body comprising side sills and end sills connecting the side sills, of a movable bottom controlling the space between the side sills and the end sills, and a side structure located at and hingedly connected with and extending laterally from each side sill in position to meet a cam beside the rail track and each side structure being normally positioned to receive and support a part of the lading constituting the load of the car and to retain a part of said lading after said movable bottom has been moved for discharge of lading through the discharge space between the side sills and said side structures being tilttable to discharge their lading through said discharge space.

18. In a mine or similar car, the combination of a wheel-supported body including side sills and end sills, axles, wheels mounted on the axles and extending above the side sills, and a side structure located beside each side sill and hingedly joined to the adjacent structure having a bottom extending outward from the adjacent side sill and said bottom having hoods extending over said wheels and said lateral structures being positioned, when in the normal position, to engage a cam, beside the rail track, for turning said structure on its hinge line.

19. In a mine or similar car, the combination of a wheel-supported body having a middle longitudinal discharge opening, a movable bottom in said opening, and a movable side structure located at each side of said discharge opening and having a bottom normally positioned to permit discharge of a part but preclude discharge of all its lading into said discharge opening when said movable bottom has been moved for discharge of lading through said opening and each such structure being movable to permit inclining its bottom for discharge of the remainder of its lading into said discharge opening.

20. In a mine or similar car, the combination of a wheel-supported body comprising a plurality of supports for each of the below-mentioned side structures and said body having a middle longitudinal discharge opening, movable means for closing said discharge opening, and a movable side structure located at each side of said discharge opening and normally resting on the above-mentioned supports on said wheel-supported body and said side structures being formed to permit making engagement with lifting means along the track for lifting said side structures into position to discharge their lading into said discharge opening, said lifting being accomplished by the forward movement of the car.

21. In a railway car of the kind described, a horizontal main frame comprising side members and end members, wheels and axles supporting said frame, brackets rising from each end of said frame, a horizontal end rail extending from side to side of the car and supported on said brackets at each end of and transverse to the frame, and a tilttable lading section at each side of said frame and supported in part by said end rails.

22. In a railway car of the kind described, a horizontal main frame comprising side members and end members, wheels and axles supporting said frame, brackets rising from each end of said frame, a horizontal end rail extending from side to side of the car and supported on said brackets at each end of and transverse to the frame, and a tilttable lading section at each side of said frame and supported by said frame and said end rails.

23. In a railway car of the kind described, a horizontal main frame comprising side members and end members, wheels and axles supporting said frame, the wheels being outside said side members, and a lading section supported substantially at the outer side of the upright plane of each main frame side member and hinged adjacent said side member for tilting at the outer side of said plane for discharge of lading into the space between said side members and said lading sections extending over said wheels when the lading sections are in normal position and exposing said wheels for accessibility when said sections are tilted upward.

24. In a railway car of the kind described, a horizontal main frame comprising side members and end members, wheels and axles supporting said frame, the wheels being outside said side members, and a lading section supported substantially at the outer side of the upright plane of each main frame side member and hinged adjacent said side member for tilting at the outer side of said plane for discharge of lading into the space between said side members and said lading sections hooded to extend over the upper

- parts of the wheels when the lading sections are in normal position and exposing said wheels for accessibility when said sections are tilted upward. 25. In a railway car of the kind described, a horizontal frame comprising side members and end members, wheels and axles supporting said frame, the wheels being outside said side members, and a tilttable lading section at each side of and hinged to the side members and extending over said wheels when the lading sections are in normal position and exposing said wheels for accessibility when said sections are tilted upward. 26. In a railway car of the kind described, a horizontal frame comprising side members and end members, wheels and axles supporting said frame, the wheels being outside said side members, and a tilttable lading section at each side of and hinged to the side members and hooded to extend over the upper parts of the wheels when the lading sections are in normal position and exposing said wheels for accessibility when said sections are tilted upward. 27. In a railway car of the kind described, the combination of axles, wheels supporting the axles, a horizontal rectangular rigid lower frame comprising side members and end members approximately in a horizontal plane cutting said wheels, a rigid second frame wider and located higher than and spaced from said lower frame and over-hanging said lower frame and comprising side members and transverse end members, means intermediate the ends of said second frame and the corresponding ends of said lower frame for rigidly supporting the second frame on the lower frame whereby said lower frame and said second frame and said intermediate supporting means constitute a strong rigid structure adapted to support lading floors and lading walls, and lading floors and lading walls applied to said rigid structure. 28. In a railway car of the kind described, the combination of a horizontal strong rectangular lower frame comprising side members and end members, axles supporting the lower frame, wheels located outside said lower frame and supporting said axles, a second strong frame wider than and supported by said lower frame and comprising side members and end members whereby said lower frame and said second frame constitute a strong rigid structure adapted to support lading floors and walls, and side lading supporting means each comprising a floor and an upright wall rising from the outer part of said floor and said floor being in a plane cutting the adjacent wheels and the inner edge of said side lading supporting means being supported by the adjacent side member of the lower frame and the outer part of said side lading supporting means being supported by the adjacent side member of the second frame. In testimony whereof I have signed my name, this 10th day of January, in the year one thousand nine hundred and thirty. 70 PERRY S. McCALLEN. 75 80 85 90 95 100 105 110 115 120 125 130
